CLAIM

The ornamental design for a bracket for retaining an air-conditioner located within a window frame, as shown and described.

DESCRIPTION

FIG. 1 is a front perspective view of the bracket for retaining an air-conditioner located within a window frame of the present design;

FIG. 2 is a front elevation view of the bracket for retaining an air-conditioner located within a window frame of the design of FIG. 1;

FIG. 3 is a rear elevation view of the bracket for retaining an air-conditioner located within a window frame of the design of FIG. 1;

FIG. 4 is a bottom elevation view of the bracket for retaining an air-conditioner located within a window frame of the design of FIG. 1;

FIG. 5 is a top elevation view of the bracket for retaining an air-conditioner located within a window frame of the design of FIG. 1;

FIG. 6 is an end view of a sleeve of the bracket for retaining an air-conditioner located within a window frame of the design of FIG. 1;

FIG. 7 is an end view of a slider of the bracket for retaining an air-conditioner located within a window frame of the design of FIG. 1; and,

FIG. 8 is a left end view of the bracket for retaining an air-conditioner located within a window frame of the design of FIG. 1.
